(57) **CLAIM**

The ornamental design for a combination tube with golf ball,
as shown and described.

DESCRIPTION

FIG. 1 depicts a perspective view from one side of the
combination tube with golf ball.

FIG. 2 depicts an elevational view of one side of the
invention of FIG. 1.

FIG. 3 depicts an elevational view of the other side of the
invention of FIG. 1.

FIG. 4 depicts a top plan view of the invention of FIG. 1.

FIG. 5 depicts a bottom plan view of the invention of FIG.
1.

FIG. 6 depicts an elevational view from the front of the
invention of FIG. 1; and,

FIG. 7 depicts an elevational view from the back of the
invention of FIG. 1.
